HEAT GENERATOR

Walter H. Harms, San Fernando, and Donovan
E. Schowalter, Upland, Calif.

Application June 25, 1948, Serial No. 35,084

4 Claims. (Cl. 47—2)

1

This invention is concerned with a heat generator and it is a general object of the invention to provide a simple, practical, highly effective heat generator, useful for heating large areas or spaces.

There are various situations in which it is necessary or desirable to provide heat. For example, various agricultural developments or rows of trees occasionally require heating as a means of protection against frost, and in various commercial establishments there are large areas that require occasional heating. In the case of agricultural establishments, for instance citrus groves, heaters have been used for a long time with varying degrees of success, one type of heater being that which involves a tower carrying an air circulator which is fed with heated air from a burner usually located at the base of the structure. Such apparatus or devices are not altogether practical in that they are generally complex and expensive to construct and are somewhat difficult to operate to best advantage.

It is a general object of the present invention to provide a heat generator practical in a situation such as has been referred to and which is characterized by a heat generator unit which in a single operation develops heat and a blast or flow of heated gases, making it unnecessary to provide separate circulating means and separate burners such as generally characterize apparatus of this general character.

Another object of the present invention is to provide a heat generator of the general character referred to wherein the generator unit is mounted on a platform supported for rotation, the platform being adjustable to operate in a plane most advantageous in the situation where the apparatus is employed.

A further object of the invention is to provide apparatus of the general character referred to wherein the support that carries the generator unit serves not only to support such unit but also as a reservoir to carry a supply of fuel for the unit.

It is a further object of the invention to provide apparatus of the general character referred to with a ladder permanently engaged with the unit rotatable on the support, which ladder is such as to enable an operator to conveniently and safely ascend to the platform that carries the generator unit, even while the apparatus is in operation.

The various objects and features of our invention will be fully understood from the following detailed description of a typical preferred form

2

and application of the invention, throughout which description reference is made to the accompanying drawings, in which:

Fig. 1 is a side view of a unit of apparatus embodying the present invention, certain of the parts being shown in section in order to illustrate details of construction. Fig. 2 is a plan section taken in the direction indicated by line 2—2 on Fig. 1, certain of the parts being broken away to show features of construction. Fig. 3 is a plan section taken as indicated by line 3—3 on Fig. 1, and Fig. 4 is a view taken as indicated by line 4—4 on Fig. 1.

The apparatus provided by the present invention involves, generally, an upwardly projecting support A, a head B located immediately above the support, means C mounting the head on the support for limited universal movement, stabilizing means D for the head normally holding it stationary in a predetermined angular position relative to the upper end of the support A, a platform E above the head, means F coupling the platform and head for free rotation of the platform relative to the head, a generator G located above the platform, mounting means H mounting the generator G from the platform E, fuel supply means J for the generator, drive means K provided to operate or rotate the platform relative to the head, a ladder L provided for reaching the platform, an instrument and control unit M coupled with various of the operating parts of the apparatus and various other elements and features as will appear from the following description.

The support A is carried on or fixed to a suitable base or foundation 10 so that it projects upwardly therefrom. In the case illustrated the foundation 10 is shown carried by and at the ground level N and the support is shown as an elongate vertically disposed structure projecting upwardly from the foundation.

In the preferred form of the invention the support A is a vertically disposed reservoir or tank, and in practice it may be advantageously formed of a cylindrical side wall 11, a bottom 12 and a top 13. The bottom 12 is shown as a flat element resting on the foundation 10 while the top 13 is shown as a spherically curved or dome-shaped element projecting upwardly from the upper end of the cylindrical side wall 11. It will be apparent from the drawings that the structure just described forms an effective reservoir or storage tank into which suitable fuel may be filled at suitable intervals through a filling opening 14, which is normally closed by a cap or plug.

Through this construction the apparatus of the present invention is wholly self-contained and does not require connection with a fuel supply line or pipe and it is simple and practical to construct the support A so that it has substantial capacity, thus enabling the apparatus to be operated for a long period of time without requiring attention.

In the preferred form of the invention the support A formed or constructed as above described is made fast to or is fixed on the foundation 10 through a means such as mounting brackets 15.

The head B is located immediately above the top 13 of the support A and in the form of the invention illustrated it is a flat plate-like structure having a central boss 16 and an annular peripheral portion 17 which is in the nature of a track the portion 17 being concentric with the boss 16.

The means C mounting the head B on the support A is a suitable structure serving to connect these elements for limited relative movement since it is desirable, in practice, to be able to vary the location or plane of the head B somewhat relative to the support A. In the case illustrated the means C is shown in the nature of a universal joint construction which involves spaced lugs 20 depending from the central portion or boss 16 of the head, lugs 17a projecting upwardly from the central portion of the top 13 of the support A, a block 18 between the head and support, a pivot pin 19 coupling the block to the lugs 20, and a pivot pin 21 coupling the block 18 to the lugs 17a on an axis at right angles to that established by the pin 19. Through this construction the head is effectively secured to the support A and yet is free to be tilted to various angular positions relative thereto, as circumstance may require.

The stabilizing means D serves to brace the head B from the support A and is operable to hold the head steady or rigidly in any desired angular position relative to the support. In the form of the invention illustrated the means D involves a plurality of circumferentially spaced rods 25 having their lower ends joined to the upper end portion of the support A and having their upper ends joined to the peripheral portion of head B. It is preferred that one end of each rod be pivotally held while the other end is adjustable. In the case illustrated the lower end of each rod 25 is pivotally coupled to an ear 26 projecting from the support A by means of a suitable pivot pin 27. The upper end of each rod extends through an ear 28 projecting from the peripheral portion of the head B and is threaded to carry nuts 29 which may be adjusted to various positions along the rod and which may be clamped or set against the ear 28. From the foregoing description it will be apparent how the adjustability provided at the inner ends of the rods 25 enables the operator to vary the angular position of the head relative to the support and how the head is most effectively stabilized relative to the support when the nuts 29 are made tight against the ears 28.

The platform E is located immediately above the head B and in practice it may be of any suitable size, form or shape, as circumstances may require. The platform is shown as a flat structure provided with a suitable guard rail 30 and located in a plane parallel with that of the head B and suitably spaced above that of head B.

The means F provided to couple the platform 75

E and head B joins these parts or elements so that the platform is freely rotatable relative to the head and rotates above an axis normal to the head and concentric therewith. In the form 5 of the invention illustrated the means F involves a centre pin 31 carried by the boss 16 of the head and projecting upwardly therefrom and anti-friction bearings 32 carried by the center of the platform E and engaged on the pin. It will be readily apparent that through suitable design or selection of anti-friction bearings the platform may be mounted on the head B to be supported in a most efficient manner and yet be free to rotate relative to the head.

10 The means F preferably includes, in addition to the structure just described, rollers 36 at the periphery of the platform so located as to engage or ride upon the annular portion or track 17 which is at the periphery of the head.

15 The generator G is located above the platform E to be carried or supported therefrom through the means H. The generator in accordance with the present invention is a unit in which suitable fuel is burned, for instance combined 20 with air, in such manner as to generate a continuous flow or blast of hot gases and which includes means by which the blast of hot gases is directed in a predetermined manner.

25 In accordance with the broader principles of 30 the invention any suitable fuel may be employed in the generator. However, it is preferred that the generator may be such as to utilize liquid fuel such as a hydrocarbon, it being convenient to store such a fuel in the support A by reason of its construction, as above described. It is to be understood, however, that gaseous fuel may be used, in which case the support A may be constructed to serve as a pressure vessel serving to 35 handle a supply of fuel under suitable pressure.

40 The particular generator G illustrated in the drawings is of the general type of device commonly employed to develop power, as for instance, for propulsion where the desired propulsion is gained through jet action. The particular generator illustrated is shown somewhat 45 diagrammatically in the drawing and as including a housing 50 in which there is a rotor involving a compressor element 51 and a turbine wheel 52. The rotary element is carried on a suitable 50 shaft 53. The compressor element delivers air under superatmospheric pressure to combustion chamber 54 which is supplied with fuel by the means J and as combustion occurs pressure is developed and the gases of combustion flow forward striking the turbine wheel 52 causing it to rotate and through this means the rotary 55 element is driven. The gases continue to flow and some further combustion occurs in chambers 56 which converge to finally deliver the 60 hot gases into a jet tube 57 from which they issue in a predetermined direction and in the form of a high velocity jet or blast.

65 Through the action of the generator G, as above described, the fuel, whether it be liquid or gaseous, is burned, and in the single operation described heat is generated and a high velocity 70 jet is generated, to the end that the heated gases are directed from the generator to flow out onto or over a large area or for a considerable distance. It will be apparent that the particular area or space heated through the action of the generator will depend upon the manner in which the generator is faced. Through the structure provided by the present invention the generator 75 may be bodily rotated by turning or rotating the

platform and the plane in which the rotation occurs may be governed by the setting of the head B relative to the support A.

The mounting means H for the generator G may, as shown in the drawings, be a simple arrangement of brackets or standards 60 which project upwardly from the platform E and to which the generator is secured so that it is rigidly coupled to the platform.

The fuel supply means J may, in practice, vary somewhat depending upon the particular fuel employed. When the support A is employed as a fuel reservoir as above described the desired supply of fuel is drawn from the reservoir by an intake pipe 61 and is handled by a suitable fuel pump unit 62 so that the desired fuel is delivered through a fuel delivery line 63 to the generator G. The fuel pump unit 62 may be an electrically operated pump unit or any suitable apparatus that will handle the fuel in the desired manner. Since the platform E carrying the generator G rotates relative to the support A from which the fuel line extends it is preferred that the pin 31 of means F and the block 18 of means C be hollow or tubular, and that the fuel line 63 be passed through the pin and block to project upwardly therefrom. When this construction is employed a suitable swivel joint 64 may be employed above the pin in the manner indicated in Fig. 1 of the drawings.

The means K serves to drive or operate the platform E relative to the head B and in the case illustrated it is shown as including a prime mover or motor 70 driving a pinion 71 which meshes with a ring gear 72. In the arrangement shown the ring gear 72 is carried by the head B concentric with the boss or hub 16 thereof, in which case the motor 70 is carried by the platform E as clearly shown in Fig. 1 of the drawings. The motor 70 may be supplied with operating current from any suitable source. For instance, when the generator G is equipped with auxiliary units such as an electrical generator operated by or from shaft 53 or some other like element current from such generator may be used to drive the motor 70 and fuel pump 62. In the drawings we have shown an electrical supply line 75 extending to pump 62 from the generator through contact rings 76 on the platform engaged by brushes 77 carried by the head B.

The ladder L provided for reaching the platform E is preferably formed of spaced parallel rails 80 joined by or carrying suitable rungs or steps 81. In accordance with the present invention the upper ends of the rails 80 are joined to the platform E preferably to the marginal or peripheral portion thereof by pivot pins 82. In the form of the invention illustrated braces 83 are provided at the upper end portion of the ladder to project laterally and upwardly from the rails 80. The braces have their upper ends pivoted to the platform by pivot pins 84 concentric with the pivot pins 82.

In accordance with the invention the lower end portion of the ladder is supported. The structure shown involves a ring 85 surrounding the lower end portion of the support A and mounted for rotation about the support through rollers 86 mounted on the exterior of the support. An arm 65 structure 87 projects from the ring and carries guides 88 which slidably carry rods 89 which are joined to the lower end portions of the rails 80 and which extend parallel therewith. Through this construction the ladder L operates with the 70 75

platform, that is, as the platform turns about the support A the ladder likewise moves about the support, and furthermore, as the platform is adjusted as to its angular position relative to the support through adjustment of head B, the ladder L is free to raise or lower but the connection between the ladder and platform is at all times maintained and the ladder is at all times braced or supported at both ends, so that it is safe and convenient to use.

The instrument or control unit M shown in the drawings is preferably an assembly of suitable control switches, valves or indicating instruments such as may be necessary or incidental to other parts of the apparatus as above described. It is preferred that the unit M be located where it is accessible to a person at the ground N, in which case it is practical to support it from the ring 85 or from the arm 87 of the ring, as shown in the drawings. It will be apparent that suitable control connections between units such as the generator G and motor 70, etc. may be carried to the unit M through a cable or conduit 90 as circumstances require. In the case illustrated the cable 90 carrying the various connections is supported by a rail of the ladder.

From the foregoing description it will be apparent that we have, by our present invention, provided an effective, efficient, heater utilizing fuel whether gaseous or liquid, in a most advantageous and in a very simple manner. By directly utilizing combustion both for heat and for the generation of a blast carrying the heat in the desired manner we have provided a simple apparatus and the overall efficiency of the structure is very high. Furthermore, it will be apparent that the structure provided by the present invention is of simple, practical form requiring a minimum number of working parts and that it is of such character as to be easily operated and controlled. By providing the operating means K independent of the generator G it is possible to generate a blast of hot gases of the desired temperature to extend the desired distance from the apparatus, and such blast can be swept through any desired arc, as for instance through 360° about the center of the structure, at any desired rate.

Having described only a typical preferred form and application of our invention, we do not wish to be limited or restricted to the specific details herein set forth, but wish to reserve to ourselves any variations or modifications that may appear to those skilled in the art and fall within the scope of the following claims.

Having described our invention, we claim:

1. In apparatus of the character described, an upwardly extending support, a generator operating to burn fuel and deliver a jet of hot gases, means supporting the generator from the support with the jet directed in a predetermined manner from the support including, a head, a universal coupling between the head and support, and a platform carrying the generator and pivotally carried by the head by a centering pin and rollers between the head and platform, the support being a reservoir carrying fuel for the generator, and means receiving fuel from the support and delivering it to the generator through the pin.

2. Apparatus of the character described including, a vertical support, a platform rotatably and tiltably supported on the upper end of the support on intersecting axes, and a ladder carried by and depending from the platform for free

rotation about the support and stabilized by the lower end portion of the support.

3. Apparatus of the character described including, a vertical support, a platform rotatably and tiltably supported on the upper end of the support, a ladder having its upper end pivotally connected to the upper end of the platform, and means stabilizing the lower end of the ladder from the lower end portion of the support including a ring rotatable on the support and a 10 sliding connection between the ring and ladder.

4. In apparatus of the character described, an upwardly extending support, a generator operating to burn fuel and deliver a jet of hot gases, and universal mounting means supporting the 15 generator from the support with the jet directed in a predetermined manner from the support said means including a stationary base member on the support and a generator carrier coupled to the base member to move universally relative 20 thereto, the support being a reservoir carrying a supply of fuel for the generator and including a fuel line extending through said member and

carrier of the universal mounting means and adapted to deliver fuel from said reservoir to said generator.
